UNITED STATES PATENT OFFICE.

CARL B. COOMBS, OF INDIANAPOLIS, INDIANA.

DESIGN FOR A RADIATOR-CAP.

58,136.

Specification for Design. Patented June 14, 1921.

Application filed March 9, 1921. Serial No. 450,976. Term of patent 7 years.

To all whom it may concern:

Be it known that I, CARL B. COOMBS, a citizen of the United States, residing at Indianapolis, in the county of Marion and State of Indiana, have invented a new and original and ornamental Design for Radiator-Caps, of which the following is a specification, reference being had to the accom-

panying drawing, forming a part thereof, in which—

Figure 1 is a top plan view and Fig. 2 a side elevation of my invention.

I claim:

The ornamental design for a radiator-cap, as shown.

CARL B. COOMBS.
